MEANS FOR INCREASING THE SUBTERRANEAN FLOW INTO AND FROM WELLS

Newton B. Dismukes, Tulsa, Okla.

Application August 26, 1948, Serial No. 46,236

5 Claims. (Cl. 166—177)

1

This invention relates to means for increasing the subterranean flow into and from wells. More specifically, it relates to apparatus for rupturing the stratum surrounding a well bore so as to provide fissures, radiating from the bore, thru which the fluid within the strata may flow.

An important object of the invention is to provide apparatus, including an expandible and contractable structure for expansion against the well bore wall so as to cause fracturing of the stratum.

Another important object is to provide apparatus for the purpose mentioned which may be employed in well bores at depths where temperatures are too high for shooting.

Still another important object is to provide apparatus which may be oriented in a well bore so that at least partial control of the direction of fracturing can be obtained. That is, fractures may be produced, extending into the stratum surrounding the well bore, substantially 180° apart. By a 90° rotation of the apparatus, if desired, other fractures may be produced spaced substantially 90° from the first fractures.

A further important object is to provide such an apparatus which may be positioned to create the fractures at a selected depth or at selected depths.

Fracturing of oil-bearing strata in this manner will have wide application in secondary recovery of oil, especially in water-flooding. Input wells can be made to take larger volumes of water and, if directional fracturing is used between wells, flooding efficiency will be greatly increased as a "line drive" will be created. In tight (low permeability) sandstones or limestones the fracturing will greatly increase production and oil recovery by primary production methods as the crevices and cracks formed will allow more rapid flow of fluid into the bore hole under smaller pressure differentials. In fields having lenticular sands these fractures may cause oil to be produced from lens not otherwise to be opened.

By the employment of the apparatus disclosed, fracturing can be accomplished without the danger of damage to casings which often accompanies shooting and, by the use of the novel apparatus disclosed, there will be no resulting fragments to be removed from the well bore.

I am aware that wedges have been employed in drilled holes to cause splitting of rocks (Peele in Mining Engineering Handbook, John Wiley & Sons, 1927; O. Bowles in The Stone Industries, McGraw Hill Book Co., 1939 pages 88-89; O. Bowles in the Technology of Marble Quarrying,

2

U. S. B. M. Bulletin, 106, pages 76-78), but there is no teaching nor hints therein nor in other authorities consulted of the apparatus and method herein disclosed nor of any apparatus constructed and arranged to be introduced into a well bore and manipulated so that portions of the outer wall thereof will be forced against the wall of a well bore to cause fracturing of the stratum surrounding the well bore.

10 Other objects and advantages of the invention will be apparent during the course of the following detailed description of the invention, taken in connection with the accompanying drawings, forming parts of this disclosure, and in which drawings:

Fig. 1 is a vertical section of one form of the invention.

Fig. 2 is a fragmentary elevation of an intermediate portion of the apparatus showing a support means for expandible and contractable feathers forming a part of the new apparatus and

Fig. 3 is a horizontal section substantially on the line 3—3 of Fig. 2.

25 Fig. 4 is a horizontal section substantially on the line 4—4 of Fig. 1.

Fig. 5 is an elevation of the novel apparatus of Figs. 1 to 4 inclusive positioned within a well bore and in a partly expanded position.

30 Fig. 6 is a horizontal section on substantially the line 6—6 of Fig. 5.

Fig. 7 is a view, partly in vertical section and partly in elevation of a slip means to anchor the lowered expandible and contractable portions of the novel apparatus.

35 Fig. 8 is a fragment of the structure of Fig. 5 in a supporting position in a well bore.

Fig. 9 is a view mostly in vertical section of a modified form of the invention within a well bore.

40 Fig. 10 is a horizontal section on substantially the line 10—10 of Fig. 9.

Fig. 11 is a view largely in vertical section of the expandible and contractable structure of a third form of the novel apparatus.

45 Fig. 12 is a view also largely in vertical section of a pressure fluid introducing and discharge means of the form of the invention also disclosed in Fig. 11.

In the drawings, wherein for the purpose of illustration are shown preferred and modified forms of the invention and wherein similar reference characters designate corresponding parts thruout the several views, the letter A designates the form of the invention not dependent upon a pressure fluid; B a modified form, employing a

pressure fluid; C a second modified form, also employing a pressure fluid; D a slips support means which may be substituted for the anchoring means of Figs. 1 to 6 inclusive for supporting the lowered expansible and contractable portions of the novel apparatus therein shown, and E designates a well and surrounding stratum.

The form A for fracturing the stratum surrounding a well bore, shown in Figs. 1 to 6 inclusive, comprises an upper rod and hammer structure 15; jar 16 in which portions of the rod and hammer structure reciprocate; a wedge 17, engaging an expansible and contractable structure of feathers 18, means 19 to support the feathers 18; anchoring means 20 for the feathers 18; and means 21 to aid in removing the apparatus A from a well bore.

Referring mainly to Fig. 1, the upper structure 15 includes a substantially vertically-reciprocating rod 25 and hammer or head 26 with the latter secured, in any approved way, such as by welding, to the lower end portion of the rod. The hammer 26 is preferably of considerable size and weight, such as 4 feet long, 4.5 inches in diameter and weighing about 216 pounds.

The hammer 26 freely reciprocates in jar 16, which latter includes a tubular body portion 30 which may have drain openings 31 suitably spaced along its length to permit the flow of fluid outwardly of the jar 16 and thus not impede reciprocation of the hammer 26. At, preferably, the upper end section of the jar body portion 30 is a suitable abutment 32 such as an inwardly-extending flange, integral with the body portion and constructed and arranged to receive the upward blows of the hammer 26 upon the lower face 33 of the abutment with the abutment extending toward the rod 25. At, preferably, the lower end section of the jar body portion 30 is a second abutment 34 which may be a plug, welded, bolted or otherwise firmly secured to the body portion 30. It is preferred that at least the upper end section of this plug be of good spall-resistant steel so as to reduce plastic deformation caused by the blows of the hammer 26 upon its upper face. The jar body portion may be of any suitable length. For example, with the size of hammer as described, this body portion may be 10 feet in length with the inserted abutment 34 about 1 foot long.

Projecting downwardly from and fixedly secured to the abutment 34 is the elongated feathers-engaging wedge 17. As may be seen, such as in Fig. 6, the wedge preferably includes a pair of opposite, downwardly-converging, substantially flat faces 40 and a pair of opposite side faces 41 meeting the faces 40 by beveled intermediate faces 42. The expansible and contractable structure comprises two feathers 18 which are substantially alike and each includes a body or wall portion 45 provided with an upwardly-extending half collar 46 whereby a shoulder 47 is provided. Each body portion 45 has an outer, preferably arcuate, peripheral face 48, an inner face 49 with a groove 50 extending longitudinally of the body portion 45 along the axial center of the face 49 from the upper end of the half collar 46 to the lower end face 51 of the body portion. The lower face 51 is preferably beveled from the outer arcuate face 48 to the inner grooved face 49.

Referring again to the groove 50, it will be noted, as in Fig. 1, that it gradually decreases in depth from the upper end of the half collar 46 to the lower end face 51. The groove has a substantially flat bottom face 52 to slidably receive

the flat face 41 of the wedge 17 and outwardly diverging side faces 53 to slidably receive the beveled face 42 of the wedge.

From the upper end of the half collar 46, downwardly for a relatively short distance (such as approximately 25 inches) a portion of the inner face 49 tapers slightly outwardly and downwardly to meet the remainder of the face 49, this taper being provided to accommodate, in the spaces provided by the tapering of the two inner faces of the assembled feathers, a pair of slots for the accommodation of pins 57 which move along the slots and which will be subsequently described. When the wedge 17 is in an inoperative position (as in Fig. 1) with respect to the feathers 18, the inner faces 49 (except for upper portions thereof) may be in contact.

Means 19 to support the feathers 18 may be provided by the walls of two cable-accommodating bores 55 extending from the inner face of each half collar 46 to the outer face thereof, substantially as shown in Figs. 2 and 3 and as may be seen, in dotted lines in Fig. 1. These bores 55 (there are four of them in the example of the form A shown) receive the intermediate portions of a suitable cable 56 (such as a quarter-inch steel cable) threaded therethru. Associated with the cable 56 are two pins 57 projecting radially, substantially 180° apart, from the wedge 17. These pins 57 are normally disposed above the half collars 46 when the wedge is in the inoperative position (as shown in Fig. 1). Auxiliary pins 58 substantially like the pins 57 may be provided, spaced below the pins 57 as a safety factor. The cable extends upwardly to and is looped over the pins 57, and its length is such that when the wedge 17 is driven downwardly to spread the feathers 18, the cable 56 will be slackened enough to allow the spread. The means 19 also function as follows: If, when the wedge 17 is drawn upwardly and the feathers do not move toward each other (because they may adhere to the wall of the well bore) the pins will draw the cable 56 taut and, of course, this will cause the feathers to move toward each other and, in addition, to move upwardly. Obviously should the pins 57 break, the auxiliary pins 58 will contact the looped cable and function in their stead.

Anchoring means 20 for the feathers 18 may comprise an elongated pipe 60 provided at its upper end portion with an inwardly-extending projection 61 which may be a flange. This includes an outwardly-and-downwardly-sloping upper face 62 and a substantially horizontal lower face 63. Normally the lower end faces 51 of the feathers rest upon the upper face 62. Extending thru the lower end portions of the feathers are a plurality of horizontally-extending screw threaded bores 64 which align axially with like bores 65 in the projection 61 and receive screws 66. These screws may be of Phosphor bronze and their function are to hold the pipe 60 attached to the feathers 18 during lowering. This construction restrains the downward and outward movements of the feathers until they are in position to be forced against the wall of the bore. However, the screws 66 are adapted to shear as the wedges 18 separate. This is effected of course, by blows upon the upper face of the lower abutment 34 of the jar 16 which cause the wedge to be driven downwardly, and the downwardly and outwardly sloping upper faces 62 of the projection 61 of the pipe 60, over which the lower end faces 51 of the feathers 18 slide.

The bottom end of the pipe 60 may be closed.

as at 67, and rests upon a suitable base, such as the bottom of the well bore.

This anchoring means 23 serves mainly to support the structure above it only until the feathers 18 separate and are forced against the wall of the bore whereupon the means 23 receive substantially none of the force of the blows of the hammer 26.

Associated with the wedge 17 is means 21 to aid in removing the apparatus A from the bore in the event the feathers 18 become stuck in the bore. This comprises a suitable abutment member, as the plate 79 which includes an outer substantially flat horizontally extending portion 71 and a socketed central portion 72 receiving the extreme lower end portion of the wedge 17 and to which it may be secured, as by screws 73. The plate portion 71 extends outwardly a sufficient distance so that it will, upon upward movement of the wedge, contact the lower face 63 of the projection 61 of the anchoring means 23, and further upward movement will tend to draw the entire tool A upwardly.

The rod 25 may be reciprocated by any suitable means, such as a cable (not shown) extending to the surface and there operatively connected, for example, to a conventional cable-tool drilling rig (not shown). During lowering of the apparatus A for positioning in the bore 39 of the well E, the feathers 18 will not spread, as is now apparent. When the closed bottom of the pipe 60 reaches the bottom 31 of the well for example, the apparatus is in a position to be operated. As the reciprocating hammer 26 strikes repeated blows upon the second abutment 34 of the jar 16, the wedge 17 connected with the head will be forced downwardly and cause the feathers 18 to move outwardly, pressing against the side wall 32 of the bore 30 and causing cracks or fissures 85 such as shown, by way of example in Figs. 3 and 4 in the stratum 36. These fissures will extend radially and, generally, with their longitudinal axes substantially 180° apart, and permit the flow of fluid which, otherwise, could not readily flow thru the stratum. Of course, the width and length of the fissures will vary, depending upon the compositions of the stratum but it has been learned that cracks or fractures extending from a well bore out into the earth strata will increase the rate of flow into, or away from, the well under the same pressure differential. The explanation of this increase is simple. A fracture has a much greater ability to transmit fluid than does the usual reservoir rock. According to one authority (Park I. Jones in Petroleum Production, vol. 1, Rheinhold Publishing Corp., 1946) the permeability of a fracture is $54,000,000 W^2$ darcys where W is the width of the fracture in inches. Thus a fracture having a width of 0.01 inch would have a permeability of 5,400 darcys, while the permeability of many commercial oil producing formations is less than 0.1 darcy. Calculations, based upon this, indicate that the controlling factor for obtaining increased flow into, or away from, a bore hole is the length of the fracture. This is true because resistance to flow within the crack is almost negligible, and also the distance which fluids must flow within the natural pores is reduced by increasing the length of fractures.

In preliminary tests made by me employing a model wedge-and-feathers apparatus of the form A, but with a wedge 20 inches long, having a taper of 1 in 40, with the feathers 10 inches long with a one to forty taper on the inside so that the outside diameter of the tool, with 10 inches of the

wedge in the feathers, was $1\frac{3}{4}$ inches, the radius of cylindrical part of the feathers was $\frac{1}{16}$ inch. This model permitted constant pressure to be exerted thruout the length of the feathers no matter what was the depth of the penetration of the wedge.

The model apparatus was first tested in a bore drilled in a body of sandstone without visible fracture prior to test fracturing (two north-south and two east-west) at hydraulic pressures up to 8150 p. s. i. (by the apparatus to be subsequently described), so that the approximate pressure would be known when using the wedge and feathers to extend the fractures. Using a two pound hammer, the wedge was driven down and the operation extended two of the four fractures 10 inches. The east-west fractures which were lengthened were those receiving the main splitting force of the apparatus, but the north-south fractures opened at the bore hole indicating tension even on the sides in contact with the feathers.

Another bore (bore B) in the same sandstone body was tested using the model apparatus. Table I gives the results.

*This measurement and all following tests were made 17 hours after the preceding test.

The test results in Table I indicate that an effective increase of one inch in tool diameter would provide a fracture 163 inches long. This distance probably depends upon the elasticity of the stratum, the more brittle strata having the longer fractures. Forty-seven hours after driving the wedge, with the apparatus in the hole, the fractures had lengthened to an average of 29 $\frac{1}{4}$ inches. The rock therefore continued to deform under the residual stresses which were set up by the wedge. Using the greater fracture length to compute the length of fracture which would result from a crack one inch wide at the bore hole, gives a length of 716 inches.

Field measurements show that a one inch wide fissure or crack at the bore would extend for substantially 50 to 80 feet to each side of the bore and calculations show that this width of fracture at the bore hole can be obtained by increasing the effective diameter of the apparatus by about 3.71 inches. An increase in the effective diameter of the apparatus of at least two inches is readily obtainable.

After fracturing has been accomplished repeated blows by the hammer 26 upon the abutment 32 generally loosen the apparatus from the bore and permit withdrawal as stated.

Referring now to Figs. 7 and 8, there is disclosed a modified form of anchoring means 22

for the feathers, which may be employed in place of the means 20 described. In the use of the means 22, the upper structure 15, jar 16, wedge 17 and means 19 are substantially like those employed in the form A.

The feathers 86 employed with the means 22 substantially like the feathers 18 except that the lowermost part of each of the former is modified by removing a section of the lowermost part of each feather body portion to provide an inwardly and downwardly sloping outer face 87 which extends to a substantially horizontal lower end face 88. Extending into the face 87 is a longitudinally-extending relatively narrow slot 89 which initially extends to the face 88 and extends short of the upper end of the face 87 and opens into a recess 90. The recess 90 is wider than the slot 89 and, preferably, slightly longer and also initially extends to the face 88. The slot 89 and adjoining recess 90 are provided for bolt shanks and nuts as shown in Figs. 7 and 8 with the shanks 91 extending into screw-threaded openings in slip bodies 92 and the nuts 93 extending into the recess 90. The nuts 93 are of greater width than the width of their slots 89. Preferably, there are two shanks 91 and nuts 93 for each sliding connection of the two slip bodies 92 and two feathers 86.

The two slip bodies 92 are somewhat triangular in vertical cross section with an outer arcuate face 92^a, lower face 92^b and inner arcuate face 92^c sloping upwardly from the face 92^b toward the face 92^a. The face 92^c slides vertically over the face 87 of the feather while the shanks 91 slide along the slot 89 and nuts 93 along the recess 90. In order to close the lower ends of the slot and recess, suitable plugs 94 may be provided and secured, as by screws to the feathers 86, after the nuts and shanks are inserted into the recesses and slots.

A separate double hinge structure 95 hingedly connects each slip body 92 to an elongated leg structure 96 with one leaf 95^a of the hinge structure 95 fixedly secured to a slip body to extend over the face 92^b and the adjacent leaf 95^b extending to a leg 96 with which it is pivotally connected as by a pintle 95^c. Normally, the hinge structure is disposed as in Fig. 7 with the knuckles of the leaf 95^b and the leg structure 96 (connected by the pintle 95^c) resting upon the lower face of the plug 94 and the leg of the leg structure 96 extending downwardly and outwardly (normally, the lower or free end of the leg structure 96 is outwardly of the vertical plane of the outer arcuate face of the upper portion of the feather 86 and in frictional contact with the wall of the bore).

Each leg structure preferably includes a pair of springs 97 extending from one leg to the other, intermediate their lengths normally urging the legs outwardly.

Associated with each hinge structure and leg structure is a resilient means 98 to prevent the hinge structure 95 from closing (to the position shown in Fig. 8) while the apparatus is being run into the well bore. This may comprise two leaf springs secured at one end of each to a feather and with their free ends projecting downwardly and outwardly from the lower flat faces of the feathers and bearing against the leaf 95^b. However when the apparatus is moved upwardly when in the desired position for setting, this will overcome the resilient grip of the springs on the hinge structures and the hinges and leg structures will be released and lowered,

causing the hinge structures to close and the leg structures to take positions, similar to the position of the leg structure 96 in Fig. 8. Since the leg structures engage the wall of the bore and the hinge structures have folded against the slip bodies lower faces 95^b, movement of the feathers 86 downwardly will cause upward sliding movement of the slip bodies over the feathers until the outer faces 92^a of the former engage the wall of the well bore. The feathers are then anchored in place and the apparatus manipulated as heretofore described to spread the feathers to cause fracturing of the stratum.

Referring now to the form B illustrated in Figs. 9 and 10, this apparatus for fracturing the stratum surrounding a well bore by exerting mechanical pressure against the wall of the bore, comprises an upper support structure 100, supporting an expandable and contractable structure 101 functioning somewhat like the expandable and contractable feathers 18 of the form A.

The upper structure 100 comprises the upper portion of an elongated tubular member 105 provided with a restricted passageway 106 which may be formed by inserting a perforated plug 107 into the bore of the member 105. Below the plug 107, the member 105 is provided with pressure fluid passageway 108 thru its wall and the member 105 may be closed, at its lower end, by a suitable plug 109.

The member 105 supports a flexible, substantially fluid-tight sleeve 110 comprising a wall of suitable material, the ends of which sleeve may be secured to the member 105 as by the two spaced-apart flanged members 111 which may have their ring portions 112 welded or otherwise secured to the member 105 so as to project outwardly beyond the periphery of the latter. Extending from each ring portion 111 is a flange 112 in gripping relationship with the ends of the sleeve. Between these ends and the outer face of the wall of the member 105 may be a compressible ring packing 114. This provides an annulus 115 defined mainly by a portion of the wall of the member 105 and sleeve 110.

The sleeve 110 may be of rubber (natural or synthetic) or heavy canvas, folded upon itself when the sleeve is not expanded. An example of a useful synthetic product is the neoprene compound having a tensile strength of 1400 p. s. i., an elongation of 820% and a durometer hardness of 47-62.

Fluid under pressure, entering the annulus from a suitable source, thru the member 105 and passageway 109, will cause expansion of the wall of the sleeve 110 against the wall of the bore and cause cracks or fissures. Such cracks or fissures 85 in the stratum E surrounding the well bore 80 are shown, by way of example, in Fig. 10.

Obviously the apparatus of form B may be lowered and raised by being attached, in any conventional manner, to the well tubing and the pressure fluid introduced by way of this tubing. A separate means for introducing the pressure fluid is disclosed in connection with the form C of the invention to be subsequently described.

Tests were made with a model apparatus constructed in accordance with the above specification of form B, employing hydraulic pressure, and made in a bore drilled in the center of a large continuous block of sandstone measuring about 36 feet by 42 feet, without visible fracture, and surrounded for a distance of 100 feet, or more of the same strata in every direction. Except for vertical load the best test was under con-

ditions identical with those in an oil field. Rupture began at 5400 p. s. i. with two slight fractures about 4 inches long. No further fracturing occurred until the pressure reached 6100 p. s. i. when two more fractures, all at right angles formed. Upon gradually increasing the hydraulic pressure to a maximum of 8150 p. s. i. which was somewhat above the safe limit of the equipment, the cracks widened and elongated with the increase in pressure. The average length of the cracks was 28 inches.

Referring now to the form C, illustrated in Figs. 11 and 12, this apparatus for fracturing the stratum surrounding a well bore by exerting mechanical pressure against the wall of the bore, comprises an upper support structure 115 which carries an expandible and contractable structure 116 as well as novel means 117 for introducing the pressure fluid to the structure 116.

The upper structure 115 shown in Fig. 12 includes a tubular element 120 having interior screw threads 121 at its upper end portion and interior screw threads 122 at its lower end portion. Preferably the intermediate portion of the tubular element 120 has a smooth bore. Cooperating with the screw threads 121 are the exterior screw threads of plug 123 having an axially-disposed screw threaded socket 124 extending from its upper or outer face 125 toward its lower or inner face 126 and a conduit-accommodating bore 127 extending from the face 125 to the face 126. Cooperating with the screw threads 122 is an adapter 128 having a body portion 129 provided with an axially-disposed, screw threaded bore 130 to receive a portion of the expandible and contractable structure 116. By this construction, a compartment 131 is provided, defined by the plug 123, adapter 128 and portions of the walls of the tubular element 120, to house a portion of the means 117.

As shown, mainly in Fig. 11, the expandible and contractable structure 116 includes a central, preferably cylindrical body 135 provided with screw threads 136 at its upper end portion to cooperate with the screw threads of the bore 130 of the adapter. Extending inwardly from the upper face 137 of the body 135 is an axially-disposed, screw threaded tapered socket 138 to receive a portion of the means 117 to be described. From the base of the socket 137 a pressure fluid passageway 139, extends axially of the body 135 to short of its lower end, whereupon the passageway 139 projects radially of the body to its outer side face, where it opens into an annulus 140 defined by portions of this face and a contractable and expandible sleeve 141 the wall of which may be substantially like the wall of the sleeve 110, except that, if desired, the sleeve 141 may gradually increase in wall thickness from its ends toward its central portion 142. The sleeve 141 is retained in place about the body 135 by spaced-apart flanged members 143 clamped against the ends of the sleeve 141. Each member 143 comprises a ring portion 144 welded or otherwise secured to the body 135 and a flange 145 extending along the sleeve 141 for a short distance and gripping the same. These flanges extend toward each other. Ring packing 146 may be disposed between the sleeve 141 and body 135, as shown in Fig. 11.

The flanged members 143 have dual functions in that each supports an end portion 147 of a helical spring 148. This end portion 147 may be fixedly secured to a flange 145. Preferably, the convolutions of each spring 148 are angular

5 10

in transverse cross section and the spring gradually decreases in cross sectional area and increases in width of convolution from the attached end portion 147 to the free or thinnest end portion 149, which latter may be disposed adjacent the central portion 142 of the sleeve. The spring 148 grips the end portion of the sleeve, and it is so constructed that, as the sleeve expands the former will also expand diametrically, being free at its end 149, and it will be this free end and adjacent portions of the spring which will expand to a greater diameter than the portions adjacent the flange 145. There will be, in fact, a tapering of the periphery of the spring from adjacent the flange 145 to the free end of the spring and this aids in preventing the flange from cutting the adjacent portions of the sleeve and also aids in preventing the ends of the sleeve from being forced, by the fluid pressure, from their contact with the member 135 and flange 145.

The means 117 for introducing the pressure fluid to the structure 116 is shown in the upper portion of Fig. 12, and includes a suitable connection 150 having a screw threaded shank portion or nipple 151 for insertion into the screw threaded socket 138 so that the connection 150 may be coupled to the member 135 and disposed within the compartment 131. The connection 150 has a pressure fluid passageway 152 from end to end and a branch pressure fluid passageway 153 extending from the intermediate portion of the passageway 152 to the upper face 154 of the connection. From the upper end of the passageway 153 a conduit 155 extends thru a sleeve 156 and is closed at its upper end by a frangible element 157.

The sleeve 156 is, preferably, of substantial construction of sufficient strength to support the weight of the structure below it, and it is screw threaded at both ends. The lower screw threads cooperate with the screw threads 124 of the plug 123.

The frangible element 157 may comprise a thin, metallic disc 158 having an axially disposed reduced portion 159 with the disc disposed over the upper end of the conduit 155.

Preferably, the element 157 is held in place in a recess 160 in the lower end of a packing gland 161 which screws into a screw threaded recess 162 in the upper end portion of the sleeve 156, and with a smaller-diametered packing gland 163 screwed into a screw threaded recess 164 in the upper end portion of the gland 161 and bearing upon the upper face of the disc 158 adjacent its periphery, a suitable packing 165 being interposed between the lower end of the gland 163 and disc 158. The passageway 166 thru the gland 163 accommodates, at its lower end, the reduced portion 159 of the frangible element 158. Resting upon the top of the reduced portion is a pin 167 which extends upwardly thru the passageway 166 (and is freely slid able therein) and outwardly of the upper end of the gland 163 where it ends in a head 168. This construction is provided so that a conventional go-devil (not shown) may be dropped to strike the head 168 and force the pin 167 to rupture the frangible element.

The go-devil may be dropped thru the conventional oil well tubing 169, the lower end of which has its screw threads coupled with the exterior screw threads at the upper end portion of the sleeve 156. This tubing 169 may be employed for the upward flow of the released pressure fluid.

Again referring to the branch pressure fluid

passageway 153 in the connection 150, a pressure fluid conduit 170 extends from this passageway, upwardly thru the compartment 131 and bore 127 to outwardly and upwardly of the plug 123 where, by conventional coupling means 171, it is coupled to a conduit 172 which may extend parallel to the tubing 169 and to the mouth of the well bore. Fluid under pressure flows thru the conduit 172, coupling means 171, conduit 170, connection 150 and passageway 139 to expand the contractible and expansible structure 116.

Of course, the devices disclosed by the several forms of the invention encounter the fluid (liquid and gas here) usually found in oil wells but such fluid is not a hindrance to the successful operation of the several devices. In fact, the hydrostatic pressure of this fluid in the well bore will exert a force on the walls 85 of the crack. Pressure applied to the fluid in the annular space around the member 105 would augment this force and assist in fracturing as soon as an initial small opening were formed.

What is claimed is:

1. In apparatus for fracturing the stratum forming the wall of a well bore, a support structure including a tubular member provided with a pressure fluid passageway and an opening to the exterior of the member intermediate its ends; an expansible sleeve structure of flexible material, having a well bore wall-engaging outer face and opposite end portions, said sleeve structure including a fluid tight portion and an outer portion said outer portion comprising a pair of helical springs, the portion of said face engaging said wall being of material which, when pressed against said wall to fracture; and means to secure the end portions of said sleeve structure to and around that portion of said tubular member at and adjacent said opening, said means being spaced from said opening and being a substantially fluid-tight means, said means including spaced-apart members, one secured to one end of one of said helical springs and the other secured to the like end of the other helical spring, the opposite end of said springs being free and spaced intermediate the length of said fluid-tight portion.

2. In apparatus for fracturing the stratum forming the wall of a well bore, a support structure including a tubular member provided with a pressure fluid passageway and an opening to the exterior of the member intermediate its ends; an expansible sleeve structure of flexible material, having opposite end portions, said sleeve structure including a fluid tight portion and an outer portion said outer portion comprising a pair of helical springs, each convolution of each spring being of springy material having a plurality of substantially flat face portions, with a flat face portion of each convolution facing outwardly of said springs and constituting a face portion engaging said wall, the portion of said face engaging said wall being of material which, when pressed against said wall to fracture; and means to secure the end portions of said sleeve structure to and around that portion of said tubular member at and adjacent said opening, said means being spaced from said opening and being a substantially fluid-tight means, said means including spaced-apart members, one secured to one end of one of said helical springs at a flat face portion of said one of said spring and the other secured to the like end of the other helical spring, at a flat face portion of said other helical spring,

the opposite ends of said springs being free and spaced intermediate the length of said fluid-tight portion.

3. In apparatus for fracturing the stratum forming the wall of a well bore, a support structure including a tubular member provided with a pressure fluid passageway and an opening to the exterior of the member intermediate its ends; an expansible sleeve structure of flexible material, having opposite end portions, said sleeve structure including a fluid tight portion and an outer portion, said outer portion comprising a pair of helical springs, each convolution of each spring being of springy material and having a plurality of substantially flat face portions, with a flat face portion of each convolution facing outwardly of said springs and constituting a face portion engaging said wall, with another flat face portion of each convolution facing inwardly and in face contact with said sleeve structure, the portion of said face engaging said wall being of material which, when pressed against said wall by fluid pressure will cause said wall to fracture; and means to secure the end portions of said sleeve structure to and around that portion of said tubular member at and adjacent said opening, said means being spaced from said opening and being a substantially fluid-tight means, said means including spaced-apart members, one secured to one end of one of said helical springs at a flat face portion of said one of said spring and the other secured to the like end of the other helical spring at a flat face portion of said other helical spring, the opposite ends of said springs being free and spaced intermediate the length of said fluid-tight portion.

4. In an apparatus for fracturing a stratum forming the wall of a well bore, a support structure including a tubular member provided with a pressure fluid passageway having an opening to the exterior of the member intermediate its ends; an expansible sleeve structure of flexible material surrounding said tubular member, said sleeve structure having opposite end portions inclosing, in a fluid tight relationship, that part of said tubular member about said opening, and a helical spring comprising a plurality of interconnected convolutions of resilient material surrounding said expansible sleeve structure and capable of effectually resisting disruption when forced against said stratum with stratum-fracturing pressure, said convolutions ending short of the middle of said expansible sleeve structure in a free end convolution; and means securing the convolution of said helical spring most remote from said free end convolution to and around an end portion of said sleeve.

5. In apparatus for fracturing a stratum forming the wall of a well bore, a support structure including a tubular member provided with a pressure fluid passageway having an opening to the exterior of the member intermediate its ends; an expansible sleeve structure of flexible material surrounding said tubular member, said sleeve structure having opposite end portions enclosing, in a fluid tight relationship, that part of said tubular member about said opening, and a helical spring surrounding said sleeve structure, said spring comprising a plurality of interconnected convolutions of resilient material capable of effectually resisting disruption when forced against said stratum with stratum-fracturing pressure, said convolutions ending, short of the middle of said expansible sleeve structure,

13

in a free end convolution; and means securing the convolution of said helical spring most remote from said free end convolution to and around an end portion of said sleeve, the other of said convolutions including the first-named convolution being freely movable over the outer surface of said fluid tight portion.
